(57) **CLAIM**
The ornamental design for a container for storing molten metal, as shown.

DESCRIPTION

FIG. 1 is a perspective view of a container for storing molten metal showing our new design;

FIG. 2 is a perspective view thereof, wherein a lid is in an open position;

FIG. 3 is a front elevational view thereof;

FIG. 4 is a rear elevational view thereof;

FIG. 5 is a front elevational view thereof, wherein the lid is in an open position;

FIG. 6 is a rear elevational view thereof, wherein the lid is in an open position;

FIG. 7 is a right side elevational view thereof;

FIG. 8 is a left side elevational view thereof;

FIG. 9 is a left side elevational view thereof, wherein the lid is in an open position;

FIG. 10 is a right side elevational view thereof, wherein the lid is in an open position;

FIG. 11 is a top plan view thereof;

FIG. 12 is a bottom plan view thereof;

FIG. 13 is a top plan view thereof, wherein the lid is in an open position; and,

FIG. 14 is a bottom plan view thereof, wherein the lid is in an open position.
